LOCK FOR DOORS AND WINDOWS

Mark R. Deyo, Peoria, Ill.

Application February 1, 1946, Serial No. 644,811

1 Claim. (Cl. 292—113)

1

The invention relates to a closure fastener, and more especially to a door or window lock.

The primary object of the invention is the provision of a lock of this character, wherein an eye hook is attached to a door or window frame, so that when the hook is engaged with an eye it can be firmly and securely held in a fastening position making it impossible to unlatch the said door or window from the outside.

Another object of the invention is the provision of a lock of this character, wherein it is readily and easily applied in a usable position for the fastening of a door or window closed with security against opening thereof, the lock being of novel construction and is unique in the assembly of its parts, which are few in number.

A further object of the invention is the provision of a lock of this character, which is simple in construction, thoroughly reliable and efficient in operation, readily and easily handled for locking and unlocking purposes, strong, durable, assuring safety in its use, and inexpensive to manufacture and install.

With these and other objects in view the invention consists in the features of construction, combination and arrangement of parts as will be hereinafter more fully described, illustrated in the accompanying drawing which discloses the preferred embodiment of the invention and pointed out in the claim hereunto appended.

In the accompanying drawing:

Figure 1 is a view showing a portion of a barrier and its frame, with the lock constructed in accordance with the invention in locking position;

Figure 2 is a plan view of the lock;

Figure 3 is an edge elevation of the actuator for the lock.

Similar reference characters indicate corresponding parts throughout the several views in the drawing.

Referring to the drawing in detail, A designates generally a portion of a horizontally swinging door, while B denotes generally a portion of a door frame therefor, yet in lieu thereof may be a window assembly, as the door and frame are merely shown for illustrative purposes in the mounting of the lock constituting the present invention and hereinafter described.

The lock constituting the present invention, 50 comprises a hook member 10 which has a bill 11 for engaging in an eye 12, adapted to be properly secured on the door A at the innermost side of the same, and this member remote from the bill 11 is formed with an eye terminal 13, while 55

2

next to the latter is a substantially half-circular or arch bend 14.

Mounted on the frame B at the vertical side thereof is a rotor in the form of a spool 15, which between the inner and outer spaced annular flanges 16 and 17 respectively, thereof is arranged an eccentric wrist pin 18, it having axial mounting with the said flanges, and loosely engaged with this pin 18 is the eye terminal 13 of the member 10. The spool 15 is hubbed on a screw 19, which is fixed in the frame B for the rotation of the rotor on a horizontal axis, as best seen in Figure 2 of the drawing.

The outer flange 17 is formed with finger engaging wings 20 so that the rotor can be manually turned, and the bend 14 affords a clearance for the hub of such spool 15 when the hook member 10 has been engaged in the eye 12 and thereby holding the bill 11 latched securely therein.

20 The latched position of the hook member 10 is clearly shown in Figure 1 of the drawing and to release the bill from the eye 12 the spool 15 is turned clockwise eccentrically lowering the hook member 10 so that it can be manually disengaged from the eye 12 by releasing the bill 11 therefrom. When the spool 15 is turned counter-clockwise the bill 11 is urged into the eye 12, with the bend 14 underslung to the hub of the said spool, whereupon the said member 10 is firmly and securely latched with the said eye 12 so that the door cannot be opened or unlocked from the outside thereof.

25 What is claimed is:

30 A latch comprising a spool-like rotor, a screw adapted to pass through the core of the rotor to engage a closure member, a wrist pin eccentrically and transversely mounted on said rotor, a hook member for engaging a keeper and pivotally mounted on said wrist pin, a bend in the hook member for the seating of the rotor therein when rotating in one direction and underslung when the said member is engaged with the keeper, and finger grips carried by the rotor for manual turning thereof.
